APPARATUS FOR SEPARATING LIQUIDS AND GASES

Filed May 6, 1926

UNITED STATES PATENT OFFICE.

KIRK W. BARTLETT, OF HAMMOND, INDIANA.

APPARATUS FOR SEPARATING LIQUIDS AND GASES.

Application filed May 6, 1926. Serial No. 107,977.

My invention relates to apparatus for separating liquids and gases and is of particular use in connection with distilling apparatus employing a casing through which distilled vapors or gases are upwardly conveyed and trays within the casing, each having a gas passage extending upwardly therethrough and separated from the liquid receiving space thereof and a liquid passage extending downwardly therefrom and receiving liquid that overflows as a result of condensation of the distillate vapors or gases, and a cap above the aforesaid gas passage and shaped and positioned to constrain the flow of gas, under pressure, from such passage through the liquid in the corresponding tray and to thereafter permit the escape of the gas from the liquid.

It is essential to prevent the upward flow of the gas through the casing unless it also flows through the liquid, as is obvious. To this end, inefficient means have hitherto been employed for sealing each tray in connection with the casing for the purpose of compelling the flow of the gasses through the gas passages in the trays. In accordance with my invention, each liquid receiving tray is seated upon a ledge that is carried by and within the casing and each tray is spaced apart from the surrounding casing wall to afford a liquid receiving pocket between the tray and the surrounding casing wall and above the corresponding ledge. The downwardly extending liquid passage pertaining to each tray communicates with the aforesaid liquid pocket to limit the level of the liquid in the pocket, this liquid passage terminating below the limiting level of the liquid in the tray. If the engagement between the trays and the ledges that support them is fluid-tight, the liquid in the pocket performs no material function. If any leakage space should intervene between a tray and its supporting ledge, such would be so slight as to permit the sealing body of liquid to be received in the corresponding pocket when the apparatus is being put into use, the upwardly flowing gas also passing through this leakage space and through the liquid in the pocket to be subject to the condensing action of this liquid, the liquid in the pocket, in such case, performing a function similar to that which is performed by the liquid in the tray.

The invention will be more fully explained in connection with the accompanying drawing in which Fig. 1 is a sectional plan view of the casing and a tray within the casing taken on line 1-1 of Fig. 2; Fig. 2 is a sectional view of a part of the casing structure with trays therein taken on line 2-2 of Fig. 1; and Fig. 3 is a view, on a smaller scale, showing the structure in elevation, some of the parts being also shown by dotted lines in this figure.

The distillate vapors or gases are admitted to the casing 1 through the inlet 2 at the bottom of the casing, the remnants of these gases or vapors after the absorption process within the casing escaping from the casing at the outlet 3 at the top of the casing. Liquid receiving trays 4 are disposed within the casing and upon ledges 5 spaced apart along the casing at suitable intervals. Each tray is formed with one or more downwardly extending passages 6 which enter the liquid at 7 in the tray below or the liquid in the bottom of the casing in the case of the lowermost tray. Each passage is formed at its upper part in the body of the tray upon the exterior of the liquid receiving space of the tray and is downwardly continued through a flattened pipe portion 6' which may be separately formed from the tray and assembled therewith. Any deficiency in the liquid in the trays is made up by liquid admitted to the top tray through the pipe 8. This liquid may be the condensate of the vapors escaping at 3. The liquid passes from the trays at points diametrically opposite the places where the liquid is received by the trays. Each tray has its encompassing wall higher where the liquid is received, as indicated at 9, and lower where the liquid overflows from the tray into the passages 6, as indicated at 10. Each liquid passage 6 terminates at its upper end above the adjacent ledge and below the top of the liquid receiving space of the tray, the arrangement being such that a liquid receiving pocket surrounds each tray, as indicated at 11, the limiting level of the liquid in this pocket being determined by the location of the upper end of the overflow passages. Each tray has one or more gas passages 12 extending upwardly therethrough and separated from the liquid receiving space thereof. Each of these gas passages has a cap 13 above it.

2
which is shaped and positioned to compel the flow of gas, under pressure, from this passage through the surrounding liquid in the tray and to thereafter permit the escape 5 of gas from this liquid.

It is desirable to have fluid-tight engagement between each tray and its supporting ledge to which end I provide each ledge with a sealing gasket 14. However, if there 10 should be leakage space between a tray and its supporting ledge, a portion of the gas flowing upwardly through the casing will pass through this leakage space into the liquid within the pocket so as to be subjected 15 to the condensing action of such liquid, the upward flow of the gas through the pockets preventing the material descent of the liquid from these pockets. By my construction, the escape of gas through the casing 20 without having it subjected to the condensing action of the liquid is prevented by means which are very simple and efficient and which, in fact, make the equipment more effective if potential leakage space exists be- 25 tween the trays and their supporting ledges.

Changes may be made without departing from the invention.

Having thus described my invention, I claim:

The combination with a casing carrying 30 a ledge therein; of a liquid receiving tray seated upon said ledge and spaced apart from the surrounding casing wall to afford a liquid receiving pocket above the ledge and between the tray and surrounding casing wall, said tray having a gas passage extending upwardly therethrough and separated from the liquid receiving space of the tray and a liquid passage communicating 35 with and extending downwardly from said liquid receiving pocket and terminating at its upper end above said ledge; and a cap 40 above said gas passage and shaped and positioned to constrain the flow of gas under pressure from this passage through the liquid in the tray and to thereafter permit the escape of gas from the liquid, a flow of gas also obtaining through the space surrounded 45 by the ledge and into said liquid receiving pocket through leakage space intervening 50 between the tray and ledge.

In witness whereof, I hereunto subscribe my name.

KENT W. BARTLETT.
